CARRIER WAVE FREQUENCY CONVERTER

Henry B. Fancher, Scotia, N. Y., assignor to General Electric Company, a corporation of New York

Application June 29, 1942, Serial No. 448,994

2 Claims. (Cl. 178—6)

My invention relates to apparatus for converting the frequency of a modulated carrier wave to a different frequency, and it has for one of its objects to provide new and improved apparatus for effecting such conversion directly, without demodulating the carrier wave to reproduce the signal as an intermediate step, and in which the final frequency of the carrier wave is controlled, with a high degree of precision, and without relation to the frequency of the carrier wave initially.

In certain situations, as in a carrier wave relay station, it is desired to convert the frequency of a carrier wave to a different frequency and to control the frequency to which the carrier wave is converted independently of the initial frequency. Where the carrier wave is modulated as with a television signal, it is cumbersome and difficult to reproduce the signal by demodulation of the initial carrier wave, and by subsequent modulation of another carrier wave of the desired frequency.

It is relatively simpler to convert the initial frequency of the carrier wave to the desired frequency by heterodyne action. It has been found that such heterodyne action should be provided in a single step to avoid multiple interaction of harmonics with the carrier wave produced when more than one heterodyne operation is used. It is, accordingly, an object of my invention to provide new and improved apparatus for converting the frequency of a television signal modulated carrier wave in a single heterodyne operation, and for controlling the converted frequency of the carrier wave independently of its initial frequency and of the television signal modulations of the carrier wave.

The features of my invention which I believe to be novel are set forth with particularity in the appended claims. My invention itself, both as to its organization and manner of operation, together with further objects and advantages thereof may best be understood by reference to the following description taken in connection with the accompanying drawing in which the single figure of the drawing illustrates schematically apparatus embodying my invention.

In the figure I have represented at 10 an antenna arranged to receive a carrier wave modulated in accordance with a television signal. This carrier wave is amplified in a television carrier wave amplifier 11 and is supplied to a frequency converter discharge device 12, which is also supplied with a second carrier wave generated in an oscillating electron discharge device

13. The carrier wave generated by the device 13 is multiplied in frequency by the frequency multipliers 14 to a frequency at which suitable heterodyne operation in the device 12 may be obtained by the waves from the antenna 10 and the waves from the frequency multipliers 14.

The carrier wave resulting from heterodyne operation in the frequency converter device 12 is amplified through a power amplifier device 15 and radiated from an antenna 16.

The frequency of the carrier wave impressed on the antenna 16 is compared in a second frequency converter device 17 with a carrier wave of standard frequency from a crystal oscillator 18. The output of the frequency converter device 17 is of a low frequency, which varies similarly to frequency variations of the carrier wave on the antenna 16, such frequency variations being detected in a rectifying discharge device 35

20 to control a discharge device 19 arranged to simulate a reactance and so connected as to control the frequency of operation of the oscillating device 13.

Upon any variation in frequency of the carrier wave at the antenna 16, the output of the converter device 17 varies in frequency in such direction that the detecting device 35 by means of the reactance device 19 varies the operating frequency of the oscillating device 13 in such sense as to return the frequency of the carrier wave at the antenna 16 to a desired value.

The frequency converter device 12 may, as illustrated, conveniently include a push-pull radio frequency power amplifier having two cathodes 20 connected together and to ground, and two control electrodes 21 and 22 connected to opposite terminals of a broadly tuned circuit including an inductance 23, a condenser 24, and a resistance 25. A center tap of the inductance 23 is connected through an inductance 41 to a suitable negative potential tap of the source 27 to supply negative bias potential to the control electrodes 21 and 22, the negative tap being connected to ground for high frequency current through a suitable condenser 28. The screen electrodes 29 of the twin electron discharge device 12 are connected together, through a condenser 30 to ground for high frequency currents, and to a positive potential tap of the source 27, of which an intermediate tap is grounded. The two anodes 31 and 32 of the device 12 are connected to opposite terminals of a tuned transmission line 33 arranged in balance, or push-pull relation, and coupled to a tuned transmis-

sion line 34 arranged as the input for the power amplifier 15.

In operation, this frequency converter device 12 acts as a balanced modulator, the output of the television carrier amplifier 11 being impressed across the tuned circuit 23, 24, 25 through a concentric transmission line 36 which terminates near the inductance 23 in a series tuned circuit 26, resonant at the frequency of the output of the amplifier 11, the inductance of the tuned circuit being coupled with the inductance 23. Since the control electrodes 21 and 22 of the device 12 are driven in parallel from the tuned circuit 41, 42, and the anodes 31 and 32 are connected with the balanced output circuit 33, substantially no energy from multipliers 14 appears in the output circuit 33, so long as there is no output from the amplifier 11.

In the presence of a carrier wave from the amplifier 11 to be converted in frequency and a wave from the multipliers 14, heterodyne action occurs in the frequency converter device 12, and a wave of heterodyne beat frequency appears in the output tuned circuit 33. The tuned circuit 33 may be tuned either to a frequency which is the sum of the frequencies from the antenna 10 and from the frequency multipliers 14, or to the frequency which is the difference thereof. It is preferred that the frequency to which the output circuit 33 is tuned be substantially different from the frequency of either one of the carrier waves impressed on the control electrodes 21 and 22, and from harmonics thereof. That carrier wave which is impressed on the control electrodes 21, 22 and which is nearer in frequency to the resonant frequency of the output circuit 33 should be impressed on the control electrodes in parallel. That is, if the carrier wave received by the antenna 10 is nearer in frequency to the output radiated from the antenna 16 than is the carrier wave from the multipliers 14, it is preferred that the carrier wave from the antenna 10 be impressed on the control electrodes 21 and 22 in parallel, and the output of the multipliers 14 on both control electrodes in push-pull, or balanced, relation.

The carrier wave from the power amplifier 15, which is supplied to the antenna 16, is also supplied through a concentric transmission line 43 to the third, or suppressor, electrode 44 of the frequency converter device 17. The electrode 44 is connected through a suitable tuned circuit 45, resonant at the frequency of the carrier wave on the antenna 16, to ground. This tuned circuit 45 is coupled with a series tuned circuit 46 connected between the terminals of the concentric conductor 43. The cathode 47 of the frequency converter device 17 is connected through a biasing resistance 48 in shunt with a suitable bypassing condenser 49 to ground, and the control electrode 50 of the device 17 is connected to ground through a tuned circuit 51. The tuned circuit 51 is resonant at the frequency of the output of an electron discharge amplifier device 52, energized from the crystal oscillator 18.

The carrier wave from the power amplifier 15 may be impressed on the second, or screen, electrode 37 of the device 17, instead of on the suppressor electrode 44. In such case, the resonant circuit 45 may be connected between the screen electrode 37 and a suitable positive potential tap on the source 27, in place of the resistance 38. In that case, the bypassing condenser 39 connected between the screen electrode 37 and the cathode 47 should be omitted, and the suppressor

electrode 44 connected directly to the cathode 47. It is preferred in the present case to impress the carrier wave from the power amplifier 15 on the suppressor electrode 44, so that the screen electrode 37 acts as an electrostatic shield between the suppressor electrode 44 and the control electrode 50, so as to reduce interaction between the waves from the power amplifier 15 and from the crystal oscillator 18.

The crystal oscillator 18 includes a suitable frequency determining element, such as a quartz crystal vibrator 53 suitably connected in circuit with a discharge device 54 to maintain oscillation of a predetermined highly stable frequency. The crystal oscillator 18 may also include suitable frequency multipliers to provide that the output frequency may be higher than the operating frequency of the vibrator 53, the device 52 being also arranged as a multiplier if desired. The anode 60 of the device 17 is connected through a tuned circuit 61 to a suitable positive potential tap of source 27, and is resonant at a frequency which is the sum or difference of the frequencies of waves from the power amplifier 15 and the crystal oscillator 18. It is preferred that the frequency at which the circuit 61 is resonant be the difference frequency, in order that a relatively low frequency may be utilized for the rectifying device 35, and in order that the changes of frequency of the waves from the power amplifier 15 may appear as equal changes of frequency of a lower frequency wave, thereby being frequency changes of such lower frequency wave of a large percentage of its lower frequency.

The heterodyne output of the frequency converter device 17 which appears in the tuned circuit 61 is amplified through a suitable amplifier 62 and appears in a tuned circuit 63.

The device 35 may conveniently comprise a pair of rectifying discharge paths respectively having anodes 70 and 71 and cathodes 72 and 73.

A tuned circuit 74, coupled to the tuned circuit 63, is connected between the anodes 70 and 71, and a center tap of the tuned circuit 74 is electrostatically coupled through a suitable condenser 75 to one terminal of the tuned circuit 63, the other terminal being grounded. A pair of resistances 76 and 77 are connected in series between the cathodes 72 and 73 of the device 35, these resistances being shunted by suitable condensers 78 and 79 having low reactance at the frequency of the output of amplifier 62. The center tap of the tuned circuit 74 is conductively connected through an inductance 80 with a point between the resistances 76 and 77 and thereby provides a return path for the flow of discharge current through the two discharge paths of the device 35. The potential on tuned circuit 63 plus that of a corresponding half of the inductance 60 of tuned circuit 74 is impressed across each of the diodes of device 35. These voltages are in quadrature phase relation where the frequency is of the value to which the circuits are tuned but the voltages on one diode become more nearly in acting relation and those on the other more nearly in opposed relation when the frequency increases, and conversely when the frequency decreases.

Thus, if the frequency of the output of amplifier 62 increases above or decreases below the frequency to which the tuned circuits 63 and 74 are resonant, the unidirectional voltages across the two resistances 76 and 77 become accordingly positive or negative in potential. So long as the output of the amplifier 62 is of the frequency to

the anode 110 and the cathode 111. Such voltage on the control electrode 92 results in leading current flowing between the anode 110 and the cathode 111, with the result that the discharge path of the device 19 appears capacitive. The magnitude of this capacitive effect is controlled by the average bias potential of the control electrode 92, which is adjusted in accordance with the average potential across the resistances 76 and 77 as explained heretofore.

Oscillations maintained in the tuned circuit 106 by the discharge device 13 are coupled through a suitable condenser 120 to the input of the frequency multipliers 14, where the frequency of such oscillations is multiplied any desired amount, to be transmitted through the concentric transmission line 40 as explained previously. Since the capacitive effect of the discharge path of the device 19 is adjusted in accordance with the average potential across the resistances 76 and 77, the frequency of the oscillations from the frequency multipliers 14 is varied through the agency of the discharge device 19 operating with the tuned circuit 106 in accordance with changes in frequency of the output of power amplifier 15. The polarity of the voltage across the resistances 76 and 77 is such that a change in frequency of the output of the frequency multipliers 14 is in a direction to maintain the output of the power amplifiers 15 at constant frequency.

By the use of the frequency multipliers 14, the frequency change in the wave transmitted through the concentric transmission line 40 in response to an average potential across the resistances 76 and 77 is made large. The frequency discriminator device 35 may be so arranged as to produce a voltage across the resistances 76 and 77 sufficient to change the simulated reactance of the device 19 by a large amount, since the device 19 need respond to no voltage except that produced by the discriminator device 35. In consequence of these two effects, a small change in frequency of the output of the amplifier 15 tends to produce a very large complementary frequency change in the output of the frequency multipliers 14, so that the stabilizing effect of the arrangement is very large. It has been found, within the range of operation of the discriminator device 35, that the output of the power amplifiers 15 is to a high degree independent of the frequency of the carrier wave received on the antenna 10. In fact, it has been found that a control ratio of 100 can be attained. That is, the output of amplifier 15 would change 1000 cycles without the control arrangement, it changes only 10 cycles with the control system operating.

In a particular case, the frequency of the carrier wave received by the antenna 10 was 163.25 megacycles, the carrier wave being modulated by a standard television signal, and the frequency of the carrier wave radiated by the antenna 16 was 67.25 megacycles. The discharge device 12 was a type 832 push-pull radio frequency beam power amplifier. The average frequency of operation of the oscillating device 13 and tuned circuit 106 was 6 megacycles, and the frequency of the output of the frequency multipliers 14 was 96 megacycles, the frequency being multiplied sixteen times in the frequency multipliers 14. The output frequency of the crystal oscillator 18 and device 52 was 60.8 megacycles, so that the output frequency of the converter device 17 was 6.45 megacycles.

In that system, a change in frequency of the output of the power amplifier 15 of 0.01 per cent produces a change in frequency of the wave applied to the discriminator device 35 of more than 0.1 per cent, and the discriminator device 35 was arranged to respond to that change in frequency and control the reactance device 19 so as to produce several per cent change in frequency of the operating device 13 and tuned circuit 106. This change in frequency was amplified sixteen times to the frequency multipliers 14, so that a very small change in frequency of the output of power amplifier 15 had a very strong tendency to restore that frequency to its assigned value.

It is desirable that the operating frequency of no part shall be a harmonic of the operating frequency of any other part of the apparatus. For example, the output frequency of the crystal oscillator 18 and device 52 should be such that the harmonics thereof differ substantially not only from the frequency of the carrier wave received by antenna 10, but also from the frequency of the carrier wave radiated by antenna 16. Similarly, the frequency of the output of converter devices 17 and 13 should not have harmonics near the carrier wave frequencies on antennas 10 and 16.

While I have shown and described a particular embodiment of my invention, it will be obvious to those skilled in the art that changes and modifications may be made without departing from my invention in its broader aspects, and I, therefore, aim in the appended claims to cover all such changes and modifications as fall within the true spirit and scope of my invention.

What I claim as new and desire to secure by Letters Patent of the United States is:

1. In a high frequency carrier relay system, a receiver for a high frequency carrier wave subject to frequency variations, a carrier wave transmitter, and a frequency converter connected to convert the high frequency carrier wave received in said receiver to a desired frequency and to supply oscillations of said desired frequency to said transmitter to control the frequency of the carrier wave transmitted thereby, and means to regulate the frequency of said carrier wave transmitted by said transmitter, said means comprising a second frequency converter constructed and arranged to produce oscillations having a frequency dependent on the frequency of said transmitted carrier but low relative thereto, a low frequency oscillator, means to control the frequency of said low frequency oscillator in response to variations in frequency of oscillations produced by said converter, and a frequency multiplier connected between said low frequency oscillator and said first converter to supply a harmonic of said low frequency oscillator to said converter to beat with the received carrier to produce said oscillations transmitted by said transmitter.
2. In a carrier relay system, the combination of a receiver for carrier waves of frequency subject to variation, a carrier wave transmitter, and frequency conversion means constructed and arranged to combine said received carrier wave with locally produced oscillations to produce oscillations to be transmitted and to supply said oscillations to said transmitter to control the frequencies of oscillations transmitted thereby, said receiver, transmitter and conversion means all operating at short wave lengths, and means to maintain constant the frequency of said trans-

which the circuits 63 and 74 are resonant, there is no net voltage across the resistances 76 and 77. Consequently, whenever the output of the power amplifier 15 varies from a frequency equal to the sum (or the difference as the case may be) of the frequency to which the circuits 63 and 74 are resonant and the frequency of the output of crystal oscillator 18 and device 52, a voltage appears across the resistances 76 and 77 whose polarity is in accordance with the direction in which the frequency of the output of the amplifier 15 differs from its desired frequency. This voltage across the resistances 76 and 77 is utilized to cause the frequency of the output of the amplifier 15 to return to its assigned frequency.

The cathode 73 is connected to ground, and the cathode 72 is connected through two serially connected resistances 90 and 91 to the first, or control, electrode 92 of the device 19. A condenser 93 is connected between ground and a point between the resistances 90 and 91, thereby forming a low pass filter circuit with the resistance 90 to prevent rapid variations of potential on the control electrode 92 in response to rapid variations in potential across the resistances 76 and 77.

Since the carrier wave received by the antenna 10 is modulated, and such modulations are retained on the carrier wave from the power amplifier 15, these modulations are applied through the frequency converter device 17 and amplifier 62 to the frequency discriminator device 35. Accordingly, any frequency change in the carrier wave applied to the frequency discriminator device 35, being either a fortuitous or intentional change of carrier frequency, produces a change of potential across the resistances 76 and 77. The television signal with which the carrier wave is modulated may include synchronizing pulses which shift or modulate the carrier frequency rather than modulating carrier amplitude above the black level, so that the resulting voltage pulses across the resistances 76 and 77 may occur at the rate of the synchronizing pulses in the television signal.

Furthermore, modulation of a carrier wave in accordance with a television signal is usually accomplished in such a fashion that only vestigial side bands are transmitted on one side of the carrier frequency. If the carrier wave be modulated in amplitude in accordance with the television signal, the greater energy in one side band may appear to the frequency discriminator device 35 as a shift in carrier frequency.

If the carrier wave be modulated in frequency in accordance with the video portion of the television signal, the major portion of the energy lies in a frequency band centered around the carrier frequency, but where vestigial side band transmission is used in such a system, the remaining energy is predominately of a frequency different from carrier frequency, and may fortuitously appear to the frequency discriminator device 35 as a shift in carrier frequency.

In order to avoid the possible effect of all these modulations of the carrier frequency, as by synchronizing pulses or video signals, on the frequency discriminator device 35, the tuned circuits 61, 63 and 74 and any tuned circuits in the amplifier 62 are so arranged as to be relatively sharply tuned near the desired carrier wave frequency. These tuned circuits therefore act to transmit the carrier wave only when it is relatively near its assigned frequency, and do not transmit it to any substantial extent when the

frequency of the carrier wave is shifted, as in accordance with the synchronizing signal.

The vertical pulses of the synchronizing signal may have a low repetition rate, such that the carrier wave is interrupted in its transmission to the resistances 76 and 77 at the rate of 30 times per second. It is not desired that such modulation of the voltage across resistances 76 and 77 influence the average carrier frequency, and accordingly means is provided whereby the bias potential on the control electrode 92 of the reactance device 19 is prevented from changing in response to such voltage changes across the resistances 76 and 77.

The means for preventing rapid voltage changes across the resistances 76 and 77, such as may be caused by interruption of the carrier wave impressed on discriminator device 35, is the low pass filter including resistance 90 and condenser 93. The time constant of this resistance 90 and condenser 93 should be sufficiently large that a rapid change of voltage on resistances 76 and 77 does not appreciably affect the potential of the control electrode 92. In the case described where the frequency of the carrier wave is modulated, for example, thirty times per second by vertical synchronizing pulses, the time constant of the resistance 90 and condenser 93 may be made of the order of $1/30$ of a second or more. That is, the resistance 90 may, for example, be about 200,000 ohms and the condenser 93 be about 0.2 microfarad.

The cathode 100 of the discharge device 13 is connected to ground, and the control electrode 101 is connected through a suitable grid bias resistance 107 to ground. The anode 102 of the device 13 is connected through an inductance 103 to a suitable positive potential tap of the source 27 of potential, which tap is connected to ground through a suitable bypassing condenser 104. The control electrode 101 of the device 13 is connected through a coupling condenser 105 to one terminal of a tuned circuit 106, of which the other terminal is connected to the tap of the source 27 which is grounded through the condenser 104. The inductance 103 and the tuned circuit 106 are electromagnetically coupled, so that the device 13 maintains oscillations in the tuned circuit 106 at its resonant frequency.

The discharge path of the reactance device 19 is connected for high frequency currents in shunt to the tuned circuit 106, so that leading or lagging currents passing through the discharge path of the device 19 change the resonant frequency of the tuned circuit 106. The anode 110 of the device 19 is connected to a point between the coupling condenser 105 and tuned circuit 106, and the cathode 111 of the device 19 is connected through a suitable biasing resistance 112 in shunt to a bypassing condenser 113 to ground. A condenser 114 is connected between the anode 110 and a control electrode 92 of the device 19, the reactance of the condenser 114 being high at the frequency of oscillation of the tuned circuit 106. The second, or screen, electrode 115 of the device 19 is connected through a suitable condenser 116 to the cathode 111, and through a resistance 117 to a suitable positive potential tap of the source 27 of potential.

The condenser 114 and the resistance 91 act as a phase shifting network connected for high frequency currents between the anode 110 and the cathode 111 of the device 19. Voltage across the resistance 91 is nearly a quarter wave advanced in phase with respect to voltage between

mitted carrier wave notwithstanding variations in frequency of said received carrier wave, said means comprising a local oscillator of fixed frequency differing by a low frequency from that of the transmitted carrier wave, means to combine oscillations having the frequency of said transmitted carrier wave with oscillations produced by said fixed frequency oscillator to produce oscillations varying in frequency in accord with variations in the transmitted carrier wave but by a percentage variation far greater than

the percentage variation in frequency of said transmitted carrier wave, a local oscillator operating at low frequency, means to regulate the frequency of said low frequency local oscillator in accord with variations in frequency of oscillations produced by said combining means, and a frequency multiplier connected between said low frequency oscillator and said frequency conversion means to supply to said conversion means said locally produced oscillations.

HENRY B. FANCHER.
